(57) **CLAIM**

The ornamental design for an endoscope operating unit, as shown and described.

DESCRIPTION

FIG. 1 is a front, top and left side perspective view of an endoscope operating unit, showing our new design;
FIG. 2 is a rear, bottom and left side perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof;

FIG. 8 is a right side view thereof; and,

FIG. 9 is an enlarged cross sectional view thereof, taken along the line 9-9 in FIG. 3.
The broken lines showing the remainder thereof are for environmental purposes only and form no part of the claimed design.
